UNITED STATES PATENT OFFICE.

OTIS L. DAVIS, OF IOWA CITY, IOWA.

AUXILIARY SWITCH FOR AUTOMOBILE LIGHTS.

Application filed October 13, 1920. Serial No. 416,748.

To all whom it may concern:

Be it known that I, OTIS L. DAVIS, a citizen of the United States, residing at Iowa City, in the county of Johnson and State of Iowa, have invented a new and useful Improvement in Auxiliary Switches for Automobile Lights; and I do hereby declare the following, when taken in connection with the accompanying drawings and the characters of reference marked thereon, to be a full, clear, and exact description of the same, and which said drawings constitute part of this application, and represent, in—

Fig. 1, a face view of an auxiliary switch for vehicle lights constructed in accordance with my invention;

Fig. 2, a longitudinal sectional view of the same;

Fig. 3, a diagrammatical view showing the circuits to the headlights and safety lamp.

This invention relates to an improvement in an auxiliary switch for automobile lights.

The object of the invention is to combine with the regular headlights a safety lamp preferably located beneath the mud guard on the right-hand side of the vehicle, which safety lamp may be lighted at the same time that the headlights are dimmed and so that while the headlights will not interfere with the view of a passing vehicle, the safety lamp will sufficiently light the road at the right so as to prevent running into a ditch or obstacle, and the invention consists in the construction and arrangement of parts as hereinafter described and particularly recited in the claims.

In carrying out my invention I employ the usual headlights 5 and 6 controlled by the usual main switch 7. I also employ a safety lamp 8, located beneath the right-hand forward mud guard. In the line between the switch 7 and the headlights I locate an auxiliary switch comprising a suitable casing 9 provided with a face plate 10 by which it may be secured in place and enclosing a shell 11 in which is mounted an insulating block 12 carrying contacts 13, 14 and 15. Above the contacts and adapted to engage therewith is a plate 16 mounted in a push button 17 which is forced outward by a spring 18

preferably mounted on a guide rod 19, and provided with a stop pin 20 by which it is prevented from being forced through the face plate. The push button is also provided with a notch 21 which will engage 55 with the face plate and lock the pin in its closed position. The wire 22 from the main switch leads to the contact 14 and from the contact 13 a wire 23 leads to the headlights, while the contact 15 is connected by a wire 24 with the safety lamp. The contacts 13 and 14 are also connected by a resistance coil 25. Under normal conditions with the push button in its outward position the plate 16 connects the contacts 13 and 14, closing a circuit to the headlights. In approaching another vehicle the push button will be forced inward so that the plate 16 connects the contacts 14 and 15. This closes the circuit to the safety lamp 8 which will be 70 brightly lighted while the circuit to the headlights is through the resistance coil 25, thus dimming the headlights 5 and 6. The safety lamp, being protected by the mud guard, will throw its rays forward and light the right-hand side of the road so that the driver can plainly see any obstructions in his path. After the vehicle has passed the push button is released, moving outward by its spring 18 and breaking the circuit to the safety lamp 8, at the same time connecting the contacts 13 and 14 so that the headlights will again be brilliantly lighted. 75

I claim:

1. A switch for a main line and an auxiliary line, including a resistance coil and a push-button carrying a plate adapted to make and break circuits through the said coil to the main line and open and close the circuit through the auxiliary line. 80

2. A switch for a main line and an auxiliary line, including two contacts in the main line, said contacts also connected by a resistance coil, a contact in the auxiliary line, a push-button normally connecting the two contacts in the main line and adapted, when pushed inward, to connect the auxiliary line with the main line and separate the two contacts in the main line. 85

3. A switch for a main line and an aux- 100

iliary line, including a casing and insulating block therein, three contacts mounted on said block, the main line connected with two of the said contacts and the auxiliary line connected with the other contact, a push-button, a contact plate mounted thereon, and a resistance coil connecting two of said contacts.

In testimony whereof, I have signed this specification in the presence of two subscribing witnesses.

OTIS L. DAVIS.
